WILLIAM L. McLALINE AND WILLARD L. BOROUGH, OF LOS ANGELES, CALIFORNIA.

SEALING CASING HEAD.

Application filed January 12, 1924. Serial No. 385,870.

This invention relates to the oil well industry and relates more particularly to a casing head which may be of especial value in the art.

5 There is a critical period in the drilling of an oil well which comes after the bit has reached or nearly reached the desired oil sand. If possible, it is advantageous to have the casing set before the well blows in. For 10 the purpose of preventing the well from blowing in before desired, the hole is kept full of heavy mud which supplies a super-hydrostatic head which holds back the gas and oil pressure, the mud entering into the 15 oil formations in a manner to clog them and prevent a premature flow of oil. After setting the casing while the well is still full of mud, the casing is ready to be cemented. During the cementing operation, it is necessary 20 to have considerable pressure to force the cement to the lower end of the casing. A casing head is used to keep a pressure in the well, the cement being pumped into the well through a lateral connection in the casing head. After the cement has hardened 25 and the casing held securely in place, the cement inside the casing is drilled out to allow the oil to flow. By keeping considerable pressure by means of mud pumped through the 30 casing head, the flow of oil may be resisted until the drill bit or other tools have been removed. After suitable piping has been 35 rigged up, the oil may then be allowed to flow from the well completely under control.

It is an object of the invention to present 40 a casing head which may have a decided advantage over other casing heads because of its use during the various stages of the well and because of its simplicity in construction as will hereinafter be explained.

It is another object to provide a casing head having a very simple packing arrangement which may be readily installed and removed.

45 The especial advantages of the invention and further objects thereof will be made obvious hereinafter.

Referring to the drawings, which are for illustrative purposes only:

50 Fig. 1 is a diagrammatic view illustrating the application of our invention.

Fig. 2 is a section taken through an embodiment of our invention.

55 Fig. 3 is a section taken on a plane represented by the line 3-3 of Fig. 2.

As shown in Figs. 2 and 3 of the drawings,

the casing head 11 of my invention comprises a body 12 which threads into the collar 13 of an oil well casing. The body 12 provides a central bore 15 through which the tubing 16 extends and has lateral openings 17 as shown.

In the counterbore or packing chamber 19 located at the upper end of the body 12, which counterbore is concentric with the bore 15, is situated the packing arrangement 21. The packing arrangement consists of a lower ring 22 which rests on the shoulder 23 of the body 12. Above the ring 22, the packing element 24 is placed; this element may 70 be made of any of the well-known packing materials, and above the packing element 24, an upper ring 25 is situated.

From Fig. 2 it will be seen that the rings 22 and 25 are identical in contour, both 75 having a flat upper face 26 and a V-shaped or ridged lower face 27. By making the rings of the same design, they are interchangeable and the possibility of improperly placing the rings is therefore obviated. 80 The tubing 16 extends through the packing arrangement 21 as shown and the coupling 29 rests on the edge 30 of the ring 25 in such a manner that the weight of the entire length of tubing is carried by the ring 25. 85 The weight on the ring 25 compresses the element 24 and the V-shaped face 27 of the ring 25 forces the element both inwardly and outwardly from the point of the V so that the element is forced in contact with 90 the tubing 16 and the counterbore 19, sufficiently to prevent the passage of mud, oil or gas therebetween.

The bonnet 35 which screws onto the body 12 at 36 may be screwed down so that 95 the beveled annular face 37 will clamp down on the coupling 29, holding the tubing 16 securely in place so that any excessive gas pressure can not dislodge it. The set screw 39 may be tightened against the collar to 100 prevent the bonnet 35 from unscrewing.

The casing head 11 is installed in the well as shown in Fig. 1, in which figure the head 11 is placed on the end of the casing 53 which extends centrally through 105 the floor of the derrick 40. Lateral pipes 41 are screwed into the opening 17 through which mud may be introduced into the well and through which the cement may be pumped for cementing the well. The pipes 110 may also be used for relieving any excessive gas pressure in the well. The tubing 16 ex-

tends upwardly and is directed laterally from the derrick, a valve 43 being provided to control the flow of oil therethrough. Another feature of the invention is that, when the packing arrangement is removed, the inside diameter of the casing head is the same diameter as that of the casing so that if necessary any tools which will enter the casing will also pass through the casing head.

10 We claim as our invention:

1. The combination of a casing head comprising: a tubular body member having a counter-bore formed therein; tubing extending through said casing head; packing means around said tubing within said counter-bore comprising a pair of interchangeable rings, each of which has an annular wedge face formed opposite a radial face thereof, and a compressible member disposed between said rings so as to be engaged by one of said wedge faces, the other of said wedge faces engaging a complementary shoulder of said counter-bore; and a coupling secured

25 to the upper end of said tubing and adapted to engage said packing means to support said tubing.

2. The combination of a casing head comprising: a tubular body member having a counter-bore formed therein; tubing extending through said casing head; packing means around said tubing within said counter-bore comprising a pair of interchangeable rings, each of which has an annular wedge face, and a compressible member disposed between said rings so as to be engaged by one of said wedge faces, the other of said wedge faces engaging a complementary shoulder of said counter-bore; and a coupling secured to the upper end of said tubing and adapted to engage said packing means to support said tubing.

30 35 40 In testimony whereof, we have hereunto set our hands at Los Angeles, California, this 7th day of January, 1924.

WILLIAM L. McLAIN.
WILLARD L. BOROUGH.
